UNITED STATES PATENT OFFICE.

CARL B. HUTCHINS, OF ALGONA, IOWA.

DISK-SHARPENER.

1,374,012.

Specification of Letters Patent.

Patented Apr. 5, 1921.

Application filed May 13, 1920. Serial No. 381,129.

To all whom it may concern:

Be it known that I, CARL B. HUTCHINS, a citizen of the United States, residing at Algona, in the county of Kossuth and State 5 of Iowa, have invented certain new and useful Improvements in Disk-Sharpener; and I do declare the following to be a full, clear, and exact description of the invention, such as will enable others skilled in the art to 10 which it appertains to make and use the same.

This invention relates to improved disk sharpeners for use in connection with plows, cultivators, and the like; and it has for its 15 object to improve upon the construction of the disk sharpener shown and described in my U. S. Patent No. 1333112 granted to me on March 9, 1920.

Another object of the invention is to provide a device of the above mentioned type 20 which is more durable, has a greater range of adjustment, is more rigid and effective in use than my patented device or other similar device known by me; it being of such construction that the parts may be readily and easily disconnected to enable the device to 25 be packed in a small package for shipment, and also permitting the device to be easily assembled by inexperienced persons.

Other objects and advantages of the 30 invention will be apparent during the course of the following description.

In the accompanying drawings forming a part of this specification in which like numerals are employed to designate parts 35 throughout the same;

Figure 1 is a perspective view of the device, illustrating the manner in which it is used.

Fig. 2 is an enlarged elevational view of 40 a device constructed in accordance with my invention.

Fig. 3 is an end elevation thereof.

Fig. 4 is an enlarged detail section taken 45 on the line 4—4 of Fig. 2, looking in the direction of the arrows.

Fig. 5 is a horizontal sectional view taken on the line 5—5 of Fig. 3.

In the drawings, wherein for the purpose 50 of illustration is shown a preferred embodiment of my invention, the letter A designates a plurality of cultivating disks mounted on a shaft B, the ends of which are journaled in the bearings C carried by 55 the depending parallel arms of the scraper-

bracket D, all of which parts are of the well-known construction.

For the purpose of supporting frame D at an elevation to space the disks A from the ground, I employ a pair of jacks or supports 1 which may be constructed from a plurality of strips of wood, arranged one on top of the other and secured together by means of a bolt 2. I do not desire to limit myself to any particular type of support, 60 and I therefore wish it to be understood that these supports may be of any other suitable construction.

In order to rotate the disks I make use of a two-part pulley 3 which is adapted to be 70 bolted on the shaft B in the manner shown. This pulley may be rotated by any suitable means, such as for instance by means of a belt (not shown).

My sharpening device comprises a pair of 75 angle-bars 4, each of which has one of its flanges directed inwardly toward the corresponding flange of the other bar in the manner shown. This inwardly directed flange is here designated by the numeral 5, while 80 the remaining flange of each bar is designated by the numerals 6, the last named flange being provided with a plurality of longitudinally spaced apertures 7, the purpose of which will hereinafter be set forth. 85 Examination of my device will disclose the fact that the lower portions of the inturning flanges 5 are removed and that the lower ends of the flanges 6 are directed inwardly 90 toward each other and the extremities bent laterally and overlapped as shown at 8. The overlapped extremities are provided with alined openings through which a screw-threaded member 9 is extended, it being held in position by means of nuts 10. It is to be 95 noted that the end of this fastening member 9 extends beyond the overlapped ends of the bars. The purpose of this construction is to provide a means for anchoring the lower ends of the bars. If desired the portion of the member which extends below the overlapped ends 8 of the bars, may be tapered in the manner shown to provide a

more effective anchoring means for the device. At their opposite ends, the angle bars 105 are connected together by means of an operating handle 11. While this handle may be of any other construction, I desire to construct it in the manner shown. Examination of the showing thereof will disclose 110

the fact that it is made up of a plurality of tubular members 12 which are fitted onto a bolt 13 which extends through the apertures provided for it in the flanges 6 of the angle-bars. With this construction it will be seen that the bars will be properly spaced apart, and at the same time a convenient form of handle will be provided.

The sharpening element is in the form of a block of abrasive material, designated by the numeral 14. This block is removably secured between the angle-bars and when in position rests against the flanges 5 and 6, being clamped in position by the last named flange. In carrying out this feature it will be seen that I make use of two bolts 15, which extend through the apertures 7, one being arranged above the abrasive element and the other being arranged below said element. To clamp the block in position it will be seen that the only thing necessary to do is to tighten the nuts on the bolts 15. By means of the longitudinally spaced openings 7 it will be seen that the abrasive element may be raised or lowered to the desired height to effectively engage the disks.

From the foregoing description it will be seen that I have perfected an extremely novel and rigid disk sharpener which may be effectively used. With it, it will be seen that the disks may be uniformly sharpened. It is to be noted that with such a device the disks will be rotated against the abrasive element instead of the latter against the disks. This method of sharpening will make it impossible to heat the disks or draw the temper. There is only one part of the device which is subjected to wear, and this part, may be easily and readily replaced. A great deal of time and expense will be saved by such a device, and due to the construction which I employ the device will be found extremely inexpensive and well worth while.

Many disk sharpeners constructed in accordance with my invention have been actually used and have proven extremely satisfactory and have produced results beyond expectations. The device in fact is no more an experiment, and is a proven article.

In using the device, it will be first necessary to place the gang of disks on a level spot. The jacks 1 may then be brought into use to raise the disks above the surface in the manner shown in Fig. 1. It may be necessary to drive a couple of stakes at the opposite ends of the jacks to prevent them from moving. A small quantity of oil may be placed on the edges of the disks to prevent undue friction. After the disks have

been found to revolve freely, the driving element may be connected to the member 3 and the shaft B set into rotation. The sharpening device may then be brought into effective engagement with the edge of the disks and the latter sharpened. The particular angle at which the sharpening element is held, will be obtained from experience with the device.

From the foregoing description taken in connection with the accompanying drawing, it is believed that persons skilled in the art to which this invention relates, will be able to obtain a thorough understanding of the same, therefore, further description is deemed unnecessary.

I claim:—

1. A sharpening device of the class described comprising a pair of spaced angle-bars connected together at their lower ends, each bar having one of its flanges inturned, the other flange being apertured, an abrasive element disposed between the apertured flanges and resting against the inturned flanges, bolts extending through said apertures, there being one bolt above and one below the abrasive element serving to clamp the flanges with which they co-act against said element, thus retaining it in place, and a handle at the upper ends of the bars. 90

2. A sharpening device of the character set forth comprising a pair of spaced angle-bars, each having one of its flanges inturned, the lower portion of each inturned flange being removed, the other flanges of the bars 95 having their lower ends directed inwardly toward each other, the extremities being bent laterally, overlapped, and provided with alined apertures, a fastening member extending through said alined apertures, 100 having one of its ends extending beyond the overlapped ends to form an anchoring spur, a piece of abrasive material secured between said bars and means including a handle connecting and spacing the upper ends of the 105 bars.

3. A sharpening device comprising a pair of spaced bars having their lower ends directed toward each other and secured together to form a point, a plurality of sleeves, 110 one being arranged between the upper portions of the bars and the others abutting the outer faces of the bars and extending laterally therefrom to form hand grips, a bolt passing through said sleeves and bars to retain these parts together, and an abrasive element held between said bars. 115

In testimony whereof I have hereunto set my hand.

CARL B. HUTCHINS.
